UNITED STATES PATENT OFFICE.

PERCY WALTERS, OF YONKERS, NEW YORK.

COOLING MEANS FOR INTERNAL-COMBUSTION ENGINES.

Application filed February 28, 1922. Serial No. 540,015.

This invention relates to internal combustion engines and more particularly to cooling means therefor.

The object of the invention is to provide 5 a simple and durable means by which air may be drawn through the space existing between the ordinary water jacket employed on most internal combustion engines and the cylinder walls of the engine and in this manner cool the engine.

It is also an object of the invention that the apparatus for drawing the air within the water jackets of engines be adapted to be operated by the crank shaft of the engine 15 to which the same may be associated.

It is a further object of the invention that the apparatus be adapted to draw the air through the water jacket of an engine and expel the same to the atmosphere at high 20 velocity.

Other objects relating to details of construction will hereinafter appear.

The invention is illustrated by way of example in the accompanying drawings in 25 which,

Figure 1 is a vertical longitudinal sectional view of an internal combustion engine to which the present invention has been applied.

Figure 2 is a detail sectional view illustrating the inlet valve employed for the water jacket.

Figure 3 is a detail sectional view illustrating the manner in which air is drawn from within the water jacket and expelled to the atmosphere.

Referring to the drawings more particularly, in Figure 1 I have shown in vertical section an internal combustion engine of the four cylinder type and in which B is the crank casing, S the crank shaft, C the cylinders and J the water jacket surrounding said cylinders in the usual manner to provide a chamber and passages through which water 45 or other cooling medium may be circulated for cooling the engine.

In carrying out the invention there is provided an inlet valve generally indicated by the reference character V which is adapted to permit air to enter within the jacket J upon a predetermined amount of suction created within the jacket. Also there is provided a pump generally indicated by the reference character P which, when operated 55 by the crank shaft S, is adapted, through

the means of valves hereafter to be described, to draw air from within the jacket J and then expel the same to the atmosphere.

The pump P consists in a cylinder 10 which is formed upon the one end of the 60 jacket J in any desirable manner. Preferably the cylinder 10 is spaced from the jacket J and supported by suitable plates as at 11. The cylinder 10 should be formed with cooling fins as at 12 so that any heat 65 developed may be easily radiated. Within the cylinder end there is suitably mounted a piston 13 which is connected to the one end of the rod 14. The other end of the rod 14 has formed therein a semi-circular 70 collar 15 which is secured to a complemental collar section 16 by bolts 17 or in any other suitable manner and thus forming a complete collar which is disposed about an eccentric 18 secured upon the shaft S. Upon rotation of the shaft S the eccentric will, of course, cause the piston 13 to reciprocate. The cylinder 10 is extended at its upper end to form a head 19 which is hollow and communicates with the interior of the cylinder 80 10 as shown and which has mounted therein an exhaust valve which consists in a valve member 20 adapted to form a closure for the passageway 21 extending through the head 19 of the cylinder 10. The valve 85 member 20 has a suitable stem formed therewith as at 22 and which is held by an arm 23 for longitudinal movement. As is obvious the weight of the valve 20 will normally retain the same in its seated position to 90 close the passage 21 and upon a predetermined amount of air pressure being exerted beneath the valve member 20 the same will rise to permit the admission of air from the passage 21.

Also there is mounted in the head 19 of the cylinder 10 a second valve member 24 which is adapted, when moved upwardly, to seat for closing the passage in the head 19 which communicates with the pipe coupling 25 and when moved downwardly to open the same passage. The valve member 24 has its stem encircled by a pressure spring 26' adapted to hold its valve in this closed position and further adapted to yield sufficiently to permit the valve to move downwardly and in its open position when a predetermined amount of suction is created in the cylinder head 19. The pipe 25 in turn communicates with a suitable casting as at 110

26 which is preferably of the shape shown and which is hollow and communicates with the space existing within the jacket J.

The inlet valve V is supported by a short pipe section 28 preferably being curved upwardly as shown and having a gauge 29 which supports the stem 30 of the valve member 31. A spring 32 encircles the stem 30 and normally holds the valve 31 in its closed position until a predetermined amount of suction is created therebeneath to draw the same downwardly. The tension of spring 32 may be regulated by the nut threaded upon stem 30. Also the stem of valve 24 carries a like nut for regulating tension of associated spring 26'.

In the operation of this device upon the engine being started the piston 13 will be reciprocated and in doing so will draw air from within the jacket J, the valve 24 operating to permit this action. The drawing of the air from within the jacket J will of course create a suction beneath the inlet valve V and operate the same to refill the space within the jacket J with air, and this in turn will be again sucked out or withdrawn by the action of the piston 13. Upon drawing the air from within the jacket J the piston will upon its upward stroke force this air to be discharged through the passage 21 by raising the valve member 20. Of course, as is shown, upon the downward stroke of the piston 13 the valve member 20 will seat itself and close the passage 21.

35 While I have herein shown and described only one form of device embodying my invention, it is to be understood that various changes and modifications may be made

herein without departing from the spirit of the invention or the spirit and scope of the 40 appended claims.

What I claim is:

1. An internal combustion engine including working cylinders and cooling jackets enclosing the cylinders, said jackets having 45 an inlet and an outlet, means including a pump chamber independent of said jackets and communicating with the said outlet, a reciprocating pump operating in said chamber to cause suction therein and in the jackets during one stroke of the pump, and regulable valves controlling the inlet and outlet of said jackets whereby to produce a partial vacuum in said jacket, and to break said vacuum and cause air to pass through 55 the jacket during the suction stroke of the pump when such suction overcomes the regulable valve controlling the inlet.

2. An internal combustion engine including cylinders and a cooling jacket enclosing the same, said jacket having an inlet and outlet, means including a chamber adjacent said outlet, a reciprocating pump adapted to cause a suction within the chamber and within the jacket during one stroke thereof and 65 compression within said chamber during its other stroke, regulable valves controlling said inlet and outlet of the jacket whereby air will be drawn through the jacket only during the suction stroke of the pump, and an exhaust valve controlling the pump chamber whereby to exhaust air from the chamber only during the compression stroke of the pump.

PERCY WALTERS.
